SAFETY DEVICE FOR STAYING MACHINES.

Application filed October 24, 1923, Serial No. 670,435, and in Great Britain October 26, 1922. Renewed April 1, 1926.

This invention relates to improvements connected with what are known as "corner staying" machines used in box-making.

With this class of machine there is considerable risk of the operative getting the hand or fingers damaged between the "anvil" and the knives or like while placing the box corners or staying material for same in position, guards and stop motions have been provided to minimize the risk.

It is our object to arrange, construct and combine with the "stayer" machine and more particularly the "anvil" portion thereof means and apparatus as hereinafter described which will cause a stoppage of the machine when undue pressure is put upon the "anvil" during the operating stroke of the knife or presser.

This arrangement will obviate the use of complicated guards which restrict output and there will be no danger to the operative.

In the accompanying drawings wherein like or similar reference letters indicate like or corresponding parts:—

Fig. 1 is a sectional end view taken approximately on the line 1—1 of Fig. 2;

Fig. 2 is a plan on line 2—2 of Fig. 1, and

Fig. 3 is a detail of the upper stop motion referred to.

In the preferred form shown of our invention we construct the "anvil" holder H (or adapt an existing one) with the usual recess for holding the anvil but instead of allowing the anvil base to bed in the said recess, we make the recess deeper and cut a number of slots or recesses A in the base, and in each recess mount on shaft C' a cam or roller like member C which projects above the face of the bed and therefore tends to raise the anvil B. Where the anvil B is in two parts, a base plate B' between same and the cam C will be employed.

These cam devices will be interconnected such as by being carried on the shaft C' which shaft will be given a tendency to turn so as to raise the cam faces and exert an upward pressure on the anvils B. This we accomplish by carrying from the shaft C a lever such as C² passing through a suitable slot formed in the anvil holder and this lever will be spring pressed by means of an arm D suitably carried from a box or frame D'. This arm is in the nature of a shaft carried by arms D² from a pivot

shaft D³ in the box D', a light spring pressure being placed on the shaft D³ so as to tend to keep the arm D in the down position.

One of the end arms D² will act as a fender or stop for the rounded end F' of a spring rod F also mounted for axial movement in the box. The other arm D² will be curved or cut away so as not to obstruct the rod F. A spring F² in the box D' tends to urge the rod F outwards, but with the end arm D² in its normal position this movement is prevented, but if an undue pressure is put upon the anvil then same will press down the cams C, raise the lever C² and arm D and allow the spring F² to operate, when the rod F may move or slide in the direction of arrow 1, Fig. 2.

The other end of the rod F is pivotally connected to the lower bifurcated end G³ of a lever G, which lever is pivoted as at G' (Fig. 1) to a stand or arm G² carried by the base G⁴ suitably attached to the machine frame. This lever G at its upper end connects to a shaft J towards the upper part of the machine and this shaft may oscillate and slide, the oscillation being obtained by means of a roller K on a lever K' attached to shaft J making contact with a cam face of a cam L on the main or upper shaft M. The usual clutch mechanism common to this class of machine is employed but we slightly enlarge the clutch ring N which is between the cam L and boss P of the operating wheel as in Fig. 3 and on a portion of the periphery of ring N we provide teeth N'. The cam L and teeth N' are so arranged that only when the presser is descending will the stop motion come into operation, therefore it is not necessary to provide teeth all the way round the periphery of the clutch ring.

On the shaft J is a lever or arm O having its end O' adapted to enter the teeth N' at any part of the downward travel of the presser. If we assume the apparatus is set and the parts as shown in Fig. 1, and the presser is descending, if an operator puts his or her finger between the presser and the anvil, the anvil will yield, lift the lever C² and arm D and release the rod F which will move along and operate the lever G and slide the shaft J in the direction of arrow 2 Fig. 3, and in sliding the shaft J the same will turn, due to said shaft J carrying

a pin J' operating in a slot J^2 of a stationary bearing carried by the machine. This causes the arm O to move and its end O' engage the teeth N' in the clutch ring, thereby by throwing out the clutch and stopping the motion.

The normal pressure of the presser on the anvil will depress the anvil, but at this portion of the stroke, which is comparatively small, the teeth N' have either passed the catch O' , or the cam L is so positioned that the roller K prevents the shaft J from turning. Assuming that the ordinary presser head has one inch to travel up or down, this being the danger zone, in this case the teeth N' will be arranged in the plate N for a distance equivalent to a travel of only $\frac{1}{8}$ of an inch, or the cam L constructed to keep out the lever and catch O O' . After this travel there is no danger as a finger could not get in between the anvil and pressers with only $\frac{1}{8}$ of an inch open, and for this portion of the traverse of the presser the tripping gear is not in operation.

To re-set the apparatus it is necessary to press or pull the lever G to disengage the lever O from the teeth and to bring the rod F back within the box and the fender or arm D will fall back into contact with the lever C^2 and depress same. If it is desired to give a longer or shorter anvil the mechanism above described in no way interferes with such adjustment as the lever C^2 will ride under the arm D .

We have found in practice that the above described apparatus is efficient and the danger of trapping of operative's hands or fingers is practically eliminated coupled with the fact that the mechanism in no way decreases the output of the machine. While we have shown and described a suitable stop motion we may vary the construction of same so long as the movement of the rod F due to pressure on the cams C causes same to be operated.

What we claim is:

1. A safety device of the class described, comprising, in combination, a vertically reciprocal anvil and means for actuating a presser adapted to cooperate therewith, a longitudinally movable member disposed in parallelism with said anvil, tension means for automatically moving said member in one direction, means for normally holding said member against longitudinal move-

ment, means operated by the anvil during its descending motion for releasing said holding means, and means actuated by said longitudinally movable member for stopping said presser actuating means. 60

2. A safety device of the class described, comprising, in combination, a vertically reciprocal anvil and means for actuating a presser adapted to cooperate therewith, a longitudinally movable member disposed in parallelism with said anvil, tension means for automatically moving said member in one direction, means for normally holding said member against longitudinal movement, means operated by the anvil during its descending motion for releasing said holding means, a pivoted lever connected to said longitudinally movable member and adapted to be swung on its pivot upon release of said member, and means operated by said lever for stopping said presser actuating means. 65 70 75

3. A safety device of the class described, comprising, in combination, a vertically reciprocal anvil and means for actuating a presser adapted to cooperate therewith, a longitudinally movable member disposed in parallelism with said anvil, tension means for automatically moving said member in one direction, a spring-pressed pivoted frame adapted normally to hold said member against movement, means operated by the anvil during its descending motion to swing said frame on its pivot thereby to release the longitudinally movable member, and means operated by said member for stopping the operation of said presser actuating means. 80 85 90

4. A safety device of the class described, comprising, in combination, a vertically reciprocal anvil and means for actuating a presser adapted to cooperate therewith, an axially movable shaft disposed in parallelism with said presser actuating means, means for rocking said shaft during its axial movement, retaining means carried by 100 said shaft for preventing operation of the presser operating means, and means operated by the anvil during its downward motion for actuating the shaft thereby to carry its retaining means into operative position 105 relative to said presser actuating means.

In testimony whereof we have signed our names to this specification.

WILLIAM RAWDON WATSON.
JOSEPH HERBERT WOOD.
